ABSTRACT OF THE DISCLOSURE

Method and apparatus for operating a spool valve in a well packer where movement of the valve actuating means is impeded by frictional engagement between the actuating means and the wall of a well. A lifting force is imposed on the actuating means at least equal to the frictional force impeding movement of the actuating movement of the actuating means. A valve actuating downwardly directed force is exerted on the actuating means, which force is in excess of the upwardly applied force.

GENERAL BACKGROUND, OBJECTS AND SUMMARY OF THE INVENTION

In performing various operations in wells, a well tool is positioned within a well bore and an actuating mechanism subsequently lowered through the well bore to engage and operate the well tool.

For example, in cementing operations, a valve packer is positioned in a well bore. In order to transmit cement to the packer for passage through the packer to an isolated formation zone, a conduit string is extended downwardly from a wellhead and coupled with a valved conduit portion of the packer. Cement flowing through the packer is controlled by a valve, the position of which is determined by longitudinal movement of the conduit string.

Before the cementing operation is commenced, i.e., before cement is transmitted through the conduit string and packer to the formation, it is desirable to close the packer valve and pressure-test the conduit string. This testing insures that, during high-pressure cementing, cement will not escape through leaks in the conduit string and cement the conduit string in the well bore above the packer. Excessive leakage, of course, would also significantly reduce the pressure of the cementing fluid so as to reduce the efficiency of the cementing operation.

The position of the conduit string, which determines the position of the valve within the packer, is detectable at a wellhead in accordance with conduit string movements ascertainable at the wellhead and variations in longitudinal force acting on the conduit string as valve actuating elements become engaged or separated.

Such wellhead observations become extraordinarily confused and difficult to evaluate where operations are conducted in "crooked" or deviated holes. Such crooked or deviated holes may include a longitudinal axis which departs in various directions from a straight longitudinal axis. It is not unknown, for example, to encounter deviations in hole straightness of such a magnitude as to yield a more or less "corkscrew" configuration.

A conduit string passing downwardly through a deviated or crooked hole will frictionally engage the wall of the hole to a substantial degree. In many instances, the frictional force imposed on the conduit string will increase as the conduit string progresses further into the hole because of increased areal contact between the outer periphery of the conduit string and the wall of the well. Thus, in deep, crooked holes, the frictional force, imped-

2

ing movement of a conduit string, will often be greater than that in shallow bore holes.

The level of this frictional force is often so high as to make it impossible at a wellhead to determine if conduit movements or changes in force acting on the conduit are a result of valve manipulations or are merely a result of the frictional interaction between the conduit string and deviated portions of the bore hole.

It thus is a basic object of the present invention to provide a method and apparatus for manipulating well tools in either straight or deviated holes so as to nullify the adverse effects of frictional interengagement between the tool actuating means and the wall of the well bore.

It is a further object of the invention to provide such a method and apparatus which requires the imposition of movement inducing force on a tool-actuating means which force exceeds the level of frictional forces so that an operator can be assured that the frictional forces do not control actuating means movement or changes in force acting on the actuating means.

It is yet another object of the invention to provide such a method and apparatus wherein the level of force required to be exerted by an operator on a tool actuating means will increase as the actuating means moves deeper into a well bore so as to tend to ensure the continuous imposition of operating force on the actuating means in excess of frictional forces acting on the actuating means, which frictional forces would tend to increase with the well depth.

Yet another object of the invention is to provide such methods and apparatus which provide, at the wellhead, a positive indication that an actuating means is in the vicinity means of a well tool to be actuated, even though the actuating means is capable of undergoing continued movement.

A related object of the invention is to provide such methods and apparatus characterized by basic structural simplicity and operational reliability and substantial resistance to the deleterious effects of corrosive fluids in a bore hole.

In accomplishing the major portion of these objectives, there is presented through the invention a method of operating a well tool where the well tool is fixedly positioned in a portion of a bore hole. A tool actuating means is lowered through the bore hole, with frictional engagement between the actuating means and the wall of the bore hole imposing a frictional force on the actuating means tending to impede movement of the actuating means. An upward force is applied to the actuating means at the general vicinity of the well tool. A downward force is applied to the actuating means in excess of the upward force, to cause the actuating means to move downwardly and actuate the well tool.

A further and independently significant aspect of the invention involves this method concept wherein the upwardly applied force is hydraulic in nature and is applied as a consequence of engagement between the actuating means and the well tool.

A still further and independently significant aspect of the invention involves this composite method concept further augmented by the application of the hydraulic force in general proportion to the pressure of well fluid in the vicinity of the actuating means.

Additional independently significant aspects of the invention entail apparatus combinations operable to perform the foregoing methods. Particular significance is attached to a basic actuating means structurally characterized by a conduit string which supports valve actuating means and a sleeve-like housing telescopingly mounted on the exterior of the conduit string. Differences in area of fluid reaction surface means carried by the conduit string and sleeve means enable the sleeve means to engage a

body portion of a packer, with the hydrostatic pressure of well fluid being operable to resist continued downward movement of the conduit string as a function of this area difference.

DRAWINGS

In describing the invention, reference will be made to preferred embodiment shown in the application drawings.

In the drawings:

FIGURE 1 schematically illustrates the actuating means of the present invention being lowered through a well bore toward a site where a retrievable valved packer is set, i.e., fixedly positioned;

FIGURE 2 provides a vertically sectioned view of the FIGURE 1 components, illustrating these components when a sleeve carried by a conduit string of the actuating means has initially engaged the body of the valved packer;

FIGURE 3 provides a vertically sectioned view of the FIGURE 1 components, illustrating the conduit string after it has moved downwardly beyond the FIGURE 2 position to effect the opening of the valve within the valved packer;

FIGURE 4 provides an enlarged, vertically sectioned view of the FIGURE 1 components showing the disposition of these components as the sleeve of the actuating means is about to engage the packer body;

FIGURE 5 provides a similarly enlarged, sectional view of the components of the assembly, disposed as shown generally in FIGURE 3;

FIGURE 6 provides an external view of the packer above actuating means of the FIGURE 1 assembly;

FIGURE 7 provides a sectional view taken on the line 7—7 of FIGURE 5.

EXAMPLE OF WELL SERVICE TO BE PERFORMED

FIGURES 1, 2 and 3 schematically illustrate the manner in which the present invention may be adapted to the pressure testing of a cement injection system.

As shown in FIGURE 1, a packer 1 has been set or fixedly positioned in a portion of a bore hole 2. Packer 1 includes a generally cylindrical or tubular body 3 and an annular, elastomeric packing means 4.

As shown in FIGURE 1, packing means 4 has been contracted axially and expanded radially outwardly into engagement with the wall 5 of the well bore 2.

As shown in the sectional views of FIGURES 2 and 3, a generally tubular slide valve 6 is telescopically mounted within a cylinder portion 7 of packer body 3. Spool or tubular valve 6 is provided with one or more ports 8, while cylinder portion 7 of body 3 is provided with one or more ports 9.

As shown in FIGURE 2, the valve 6 is disposed in an upper position, with the ports 8 and 9 axially separated and mutually sealed from each other. With this arrangement, fluid communication between the well annulus zone 10, beneath the packer 1, and the interior passage 11 of the packer body 3 and spool valve 6 is blocked.

Downward movement of the valve 6 serves, as shown in FIGURE 3, to bring the port means 8 and 9 into radially aligned relationship so as to provide fluid communication between the zones 10 and 11.

As will here be appreciated, the packer means 1 has been schematically illustrated. In order to avoid obscuring the present invention, structural details of the seating mechanism, slips, wedges, expanding shoes have been deleted. Suffice it to here indicate that a packer assembly, consistent with the illustrated application of the present invention comprises an "E Z Drill S.V. Squeeze Packer" manufactured by the Halliburton Company of Duncan, Okla.

As shown in FIGURES 1, 2, and 3, a valve actuating tool 12 is lowered from a wellhead through a bore hole 2 on a conduit string 13.

The function of actuating means 12 is to sealingly engage the packer means 3, pressure test the conduit string 13, and subsequently enable fluid to be pumped under high pressure from a wellhead, through the conduit string 13 and packer passage 11, and outwardly through the aligned ports 8 and 9 into the zone 10 for a "squeeze" cementing operation.

Pressure testing is accomplished with the valve 6 shown in the upper or closed position illustrated in FIGURE 2. Cement is injected through the conduit string 13 and into the zone 11 when the valve 6 is in the lower position illustrated in FIGURE 3.

As shown schematically in FIGURES 1, 2 and 3, the actuating tool comprises a support means or central conduit portion 14 and a sleeve-like cylindrical member or movable means 15 telescoping mounted on the exterior of conduit portion 14. This conduit portion may be considered an integral part of conduit string 13.

Sleeve 15 is operable to move telescopingly on conduit string 14 within limits defined by abutment means 16 and 17. Abutment means 16 is operable to engage the upper end 18 of sleeve 15 so as to limit downward movement of conduit 14 relative to sleeve 15. Abutment means 17, formed on the interior of sleeve 15 functions as a cylinder head operable to engage a piston-like shoulder 19 formed on the exterior of conduit 14 and thereby limit upward movement of the conduit 14 relative to the sleeve 13.

As shown in FIGURE 3, generally annular shoulder or piston 19 is operable to move longitudinally and telescopingly through an annular or cylinder-like cavity 20 extending longitudinally downwardly from cylinder head 17.

To effect the previously discussed sequence of pressure testing and cement injection operations, the actuating means 12 is lowered toward the fixedly positioned or previously set packer 1 as shown in FIGURE 1.

The lower end 21 of cylinder 15 is brought into abutting engagement with the upper end 22 of the packer body 3 as shown generally in FIGURE 2. At the point shown in FIGURE 2, where the lower sleeve end 21 first engages the upper end 22 of the packer body 3, the lower extremity 23 of the conduit 14 is in the general vicinity of the spool valve 6 but has not engaged the spool valve 6 for movement inducing purposes.

With the components disposed as shown in FIGURE 2, continued downward movement of the conduit 14 will be effected with the operator at a wellhead observing that a substantial lifting force is acting on the lower end of the conduit string 14. This lifting force results from a difference in fluid reaction surfaces in the actuating means 12, which difference serves to produce a net lifting force acting on the lower end of the conduit string 14 and a net downwardly directed force acting on the sleeve 15 in response to the pressure of well bore fluid in the annular zone 24 generally adjacent the actuating sleeve 15. A more detailed discussion of this fluid reaction phenomena will be presented subsequently.

It is sufficient here to say that the reaction force acting upwardly on the lower end of the conduit string 14 exceeds the frictional force acting on the conduit 13 as a result of engagement between the exterior of the conduit 13 and crooked or deviated portions of the well bore wall 5.

Thus, continued downward movement of the conduit 14, beyond the position illustrated in FIGURE 2, can be effected only when the force acting downwardly on the conduit string 13 exceeds the frictional force tending to impede movement of this conduit string.

As the lower conduit portion 23 moves downwardly, an abutment 25 at the lower extremity of the conduit 14 engages an annular seat 25 formed on the interior of the

spool valve 6. With the abutments 25 and 26 thus engaged, continued downward movement of the conduit 14 will cause circumferentially spaced resilient finger-like latches 27, carried at the upper end of the sleeve 26, to be cammed radially inwardly by engagement between latch cam lugs 27a and a camming shoulder 28 formed on the interior of conduit body 3. This inward camming of the latching fingers 27 will cause radially inwardly facing latching lugs 29, carried at the upper extremity of the fingers 27, to latchingly engage a portion of the annular recess 30 formed on the outer extremity of the lower portion 23 of the conduit 14.

Movement of the thus interlatched conduit 14 and spool valve 6 will continue until the abutment 16 engages the abutment 18. This engagement, coupled with engagement between the abutments 21 and 22, will determine the extremity of lower movement of the latched valve 6 and conduit 14. At this lowermost movement extremity, the ports 8 and 9 will be radially aligned as shown in FIGURE 3.

Upward movement of the interlatched conduit string 14 and valve 6 sufficient to close the packer valve may be effected merely by raising the conduit string 13 through an axial increment sufficient to restore the valve 6 to a closed position. Complete withdrawal of the conduit 14 from the valve 6 may be effected by continued upward movement of the conduit string 14 sufficient to return the camming lugs 27a to an annular recess 31 located immediately above the camming shoulder 28. Recess 31 extends radially outwardly of the interior of the packer body 3. Once the camming lugs 27a are brought into radial alignment with this recess 31, these lugs, because of the resilience of the fingers 27, will flex radially outwardly and simultaneously latch the valve 6 in a closed position and free the latching lugs 29 from engagement with the recess 30 of the conduit 14.

With conduit 14 telescopingly inserted within the interior of packer body 3, an annular seal or gasket 32 provides sealing engagement between the conduit 14 and the packer body 3. However, this gasket 32 enables telescoping movement of the conduit 14 relative to the packer body 3 to take place.

With the apparatus components disposed as shown in FIGURE 2, i.e., with the conduit 14 sealingly engaged with the packer body 3, fluid within the conduits 13 and 14 may be pressurized to pressure test the tubing 13 for leaks.

This test may be conducted when the sleeve 15 initially engages the packer body upper end 22 i.e., without manipulating the valve 6, if the valve 6 is known to be in an upper or closed position. In order to ensure this valve position, it may be desirable to manipulate the conduit string, first downwardly then upwardly, to move the valve 6 to an open position and restore it to a closed position.

After the tubing test has been conducted, the conduit string 14 is moved downwardly to dispose the spool valve 6 in the open position shown in FIGURE 3. With the spool valve open, cement may then be injected, under high pressure, through the conduit string 13 and conduit 4 and packer body 3, to flow outwardly from the packer passage 11 through the aligned ports 8 and 9 and into the annular zone 10.

With the basic mode of operation of the invention having been described, it now becomes appropriate to consider structural details.

STRUCTURAL AND OPERATIONAL DETAILS

Structural details of the apparatus are illustrated in FIGURES 4 through 7.

As there shown, conduit 14, which may be considered as the lower end of conduit string 13, comprises a generally cylindrical, lowermost member 14a. Lower portion 14a has an externally threaded upper end 14b. This upper end 14b is threadedly connected with a female threaded

coupling portion 14c formed at the lower end of an upper portion 14d of conduit means 14. As illustrated, conduit portion 14d supports and defines the piston-like abutment 19.

Conventional, threaded pipe coupling means 14e serve to connect conduit portion 14d to the portion of conduit string 13 which provides the abutment or stop 16.

As shown in FIGURES 4 and 5, cylinder 20 is defined by a cylindrical wall 20a which extends axially downwardly from the generally frustoconical cylinder head wall 17.

For purposes of conforming engagement, piston defining abutment 19 is also frustoconically configured. Thus, downward movement of sleeve 15 on conduit 14 is limited by more or less conforming engagement between the abutment means 17 and 19.

The upper end of cylinder 20 is closed by engagement between conduit means 14 and a generally cylindrical wall 33. This wall 33 extends axially upwardly from the inner edge 17a of cylinder head 17. One or more O-ring type seals 34 may be provided to enhance the seal between wall 33 and an axially extending, generally mating cylindrical wall 35 formed on conduit portion 14d.

Piston 19 is defined by generally frustoconical and radially outwardly extending wall 19a and by a cylindrical side wall 36. Cylindrical wall 36 is telescopingly and sealingly engaged with the cylinder wall 20a. Sealing between the walls 36 and 20a may be enhanced by one or more O-ring type gaskets 37a carried by the cylindrical wall 36.

As shown, cylindrical walls 36 and 20a are generally of the same diameter, with this same diameter being somewhat larger than the generally same diameter of the mating walls 33 and 35.

This difference in diameter provides a "differential" annular cross-sectional area A, shown in FIGURE 7. Area A determines the level of well bore fluid induced pressure which acts upwardly on the lower end of conduit means 14 and downwardly on the sleeve means 15.

As will here be understood, the tool components are assembled so that there is little or no air in the cylinder chamber 37 when the tool is in the contracted position shown in FIGURE 4.

When the tool is moved to the extended position shown in FIGURE 5, there will be some tendency to produce a vacuum in the cavity 37. The level of vacuum induced forces generated within the cavity 37 are of such small consequence that they may be ignored in the context of the well bore fluid generated pressures.

As shown in FIGURES 4, 5 and 6, one or more ports 38 extend radially through the upper end of sleeve means 25 above the seals 34 so as to expose the upper sleeve end and the upper end of wall 35 to the pressure of well bore fluid.

Somewhat similarly, one or more radially extending ports 39 intersect the lower end of sleeve means 15 and provide fluid communication between well bore fluid and the lower end of sleeve 15 and the lower end of wall 36.

It will thus be apparent that with the abutment means 21 and 22 abuttingly engaged, the pressure of well bore fluid adjacent the sleeve 15 will exert a net lifting force on the conduit means 14. In this connection, it will be noted, by reference to FIGURES 4 and 5, that abutment means 21 and 22 may each be frustoconically configured so as to facilitate generally mating engagement.

The diameter of wall 20a will be determinative of the upwardly directed force exerted by well bore fluid pressure on the conduit means 14 by way of the port means 38. The smaller diameter of wall 35 will be determinative of downwardly directed fluid pressure exerted by the pressure of well bore fluids on the conduit means 14 by way of the ports 39.

The difference in cross-sectional area between the circular cross sections, defined by walls 35 and 20a, provides

ie differential area A which is determinative of the net lifting force which well bore fluid pressure will exert on the conduit means 14. For practical purposes, this area A may be viewed as the cross-sectional area of the annular piston 19, i.e., the annular cross-sectional area of the piston means 19 extending between the walls 35 and 36. This cross-sectional area, of course, for practical purposes may be viewed as being the same as the cross-sectional area of the annular cylinder means 20 existing between the walls 33 and 20a.

These "practical" approaches to piston cross-sectional area and cylinder cross-sectional area ignore the fairly inconsequential clearance gaps between mating cylinder and piston surfaces.

Here again, from the standpoint of making practical computations, the hydrostatic pressure of well bore fluid acting on conduit means 14, by way of ports 38, may be viewed as being the same as the hydrostatic pressure of well bore fluid acting on conduit means 14 by way of port means 39. This practical approach ignores the difference in elevation of port means 38 and 39, but this difference in elevation is of immaterial consequence in the context of the well depth where the sleeve means 15 will be operating.

At this point, some reference may be made to the change in forces imposed on the conduit means 14 and string 13 as a result of engagement between the sleeve abutment 21 and the packer body abutment 22.

As the actuating means 12, which may be viewed as including the sleeve 15 and the conduit string 13 with its continuation portion 14, is lowered through a well bore, the differential area induced fluid pressure forces acting on sleeve 15 will offset the differential area induced fluid pressure forces acting on the conduit 14. This offsetting of forces is a consequence of the engagement between the abutments 19 and 17. However, once the abutments 21 and 22 are brought into full engagement, the ability of the differential area forces acting on sleeve 15, to offset the differential area forces acting on the conduit means 14, is nullified. Thus, continued downward movement of the conduit means 14, once the abutments 21 and 22 are fully engaged, takes place with differential area induced fluid pressure forces acting effectively upward on the conduit means 14. Thus, at a wellhead, an operator will be able to ascertain when the abutments means 21 and 22 have become engaged because the weight indicator at the wellhead connected with the conduit string 13 will indicate an apparent lessening in the weight of the conduit string. This apparent lessening of course, will result from the differential area fluid generating force acting on the conduit means 14.

To offset this string "lightening," it will be necessary for the operator at the wellhead to place a greater downwardly directed load on the conduit string 13. This would generally be effected by reducing the extent to which a conduit string supporting device exerts an upward restraining force on the upper end of the conduit string 13.

Here again, it will be appreciated that the invention is specifically contemplated for operation in deviated or crooked holes where the differential area induced, hydrostatic force acting on the conduit means 14 will be of such a level as to at least equal and preferably exceed the anticipated frictional force acting between the crooked wall of the well bore and the exterior of the conduit string 13. For example, if it is anticipated that the frictional force will be on the order of up to about five thousand pounds, the cross-sectional area A may be such as to provide a differential area-induced lifting force acting on the conduit means 14 on the order of magnitude of sixty-two hundred pounds.

Significantly, this force may be produced with an extremely small area A. With a cross-sectional area A as small as one square inch, and with the sleeve 15 being disposed in a well bore beneath about one thousand feet

of conventional drilling mud, this level of differential area force would be produced.

By manipulating the conduit string 14 for valve movement purposes at a force level above that required to overcome frictional force, an operator can be sure that conduit string movements and variations in conduit string force detected at the wellhead are not being governed, or induced by, frictional interaction between the well bore and the conduit string.

10 SUMMARY OF ADVANTAGES AND SCOPE OF INVENTION

A principal advantage of the invention resides in the provision of an apparatus and method for enabling well bore manipulations to be effected while obviating interference from friction induced forces.

Another major advantage of the invention resides in the provision of a well tool actuating apparatus and method which provides an indication that an actuating component is near a well tool even though the actuating component is able to continue movement toward the well tool. Thus, prior to the time that the conduit abutment 25 engages the sleeve valve abutment 26, the engagement between the abutments 21 and 22 will enable the differential area A to commence to produce an effective hydraulic force acting upwardly on the conduit means 14.

It is also significant to here note that the differential area generated force will increase with the operating level of the sleeve means 15. Thus, in deeper wells, where greater frictional force would be anticipated, a higher differential area-induced lifting force acting on the conduit means 14 will result.

It is also noteworthy that the differential area induced lifting force does not become effective until the sleeve 15 actually engages the packer 1. Thus, during the initial lowering operation, the differential area effect does not impede conduit string movements.

The structurally simple nature of the conduit means 14 and the sleeve means 15 contributes to basic ease of fabrication, ease of maintenance, and ruggedness. Such ruggedness contributes to operational reliability. The nature of the components is such as to minimize vulnerability of the apparatus to corrosion and clogging.

In describing the invention reference has been made to a preferred embodiment. However, those skilled in the well tool art and familiar with the disclosure of the invention may envision additions, deletions, substitutions or other modifications which would fall within the purview of the invention as set forth in the appended claims.

We claim:

1. A method of operating a well tool, said method comprising:
fixedly positioning a well tool in a portion of a bore hole;
lowering tool actuating means through said bore hole, with frictional engagement between said actuating means and the wall of said well bore imposing a frictional force on said actuating means tending to impede movement of said actuating means when said actuating means is in the general vicinity of said well tool;
causing the application of an upward force to said actuating means, at the general vicinity of said well tool, at least equal to said frictional force; and,
applying a downward force to said actuating means in excess of said upward force to cause said actuating means to move downwardly and actuate said well tool.

2. A method of operating a well tool, said method comprising:
fixedly positioning a well tool in a portion of a deviated bore hole;
lowering tool actuating means through said deviated bore hole, with frictional engagement between said actuating means and the wall of said well bore im-

posing a frictional force on said actuating means tending to impede movement of said actuating means when said actuating means is in the general vicinity of said well tool;
 engaging said actuating means with at least a portion of said well tool and thereby causing the application of an upwardly directed hydraulic force to said actuating means in response to engagement between said actuating means and said well tool, with said upwardly directed force being at least equal to said frictional force;
 applying a downwardly directed force to said actuating means in excess of said upwardly directed force to cause said actuating means to move downward and actuate said well tool.

3. A method of operating a valve in a well tool, said method comprising:

fixedly positioning a valved well tool in a portion of a deviated bore hole;
 lowering tool actuating means including a conduit string through said deviated bore hole, with frictional engagement between said actuating means and the wall of said well bore imposing a frictional force on said actuating means tending to impede movement of said actuating means when said actuating means is in the general vicinity of said well tool;
 engaging said actuating means with at least a portion of said well tool and thereby causing the application of an upwardly directed hydraulic force to said actuating means, in response to engagement between said actuating means and said well tool and in proportion to the pressure of well fluid in the vicinity of said actuating means, with said upwardly directed force being at least equal to said friction force; and applying a downwardly directed force to said actuating means in excess of said upwardly directed force to cause said actuating means to move downward and actuate a valve in said well tool.

4. A well tool apparatus comprising:

a well tool fixedly positioned in a portion of a bore hole and having actuatable means associated therewith;
 tool actuating means operable to be lowered through said bore hole, with frictional engagement between said actuating means and the wall of said well bore imposing a frictional force on said actuating means tending to impede movement of said actuating means when said actuating means is in the general vicinity of said well tool;
 means for applying an upward force to said actuating means, at the general vicinity of said well tool, at least equal to said frictional force; and
 means for applying a downward force to said actuating means in excess of, and during the application of, said upward force to cause said actuating means to move downwardly and actuate said actuatable means associated with said well tool.

5. A well tool apparatus comprising:

a well tool fixedly positioned in a portion of a deviated bore hole and having actuatable means associated therewith;
 tool actuating means operable to be lowered through said deviated bore hole, with frictional engagement between said actuating means and the wall of said well bore imposing a frictional force on said actuating means tending to impede movement of said actuating means when said actuating means is in the general vicinity of said well tool;
 means for applying an upwardly directed hydraulic force to said actuating means in response to engagement between said actuating means and said well tool, with said upwardly directed force being at least equal to said frictional force; and
 means for applying a downwardly directed force to said actuating means in excess, and during application

of, said upwardly directed force to cause said actuating means to move downward and actuate said actuatable means associated with said well tool.

6. A well tool apparatus comprising:

a well tool fixedly positioned in a portion of a deviated bore hole and having an actuatable valve means therein; tool actuating means including a conduit string operable to be lowered through said deviated bore hole, with frictional engagement between said actuating means and the wall of said well bore imposing a frictional force on said actuating means tending to impede movement of said actuating means when said actuating means is in the general vicinity of said well tool;

means for applying an upwardly directed hydraulic force to said actuating means, in response to engagement between said actuating means and said well tool and in proportion to the pressure of well fluid in the vicinity of said actuating means, with said upwardly directed force being at least equal to said friction force; and

means for applying a downwardly directed force to said actuating means in excess of said upwardly directed force to cause said actuating means to move downward and actuate said valve means in said well tool.

7. An apparatus for performing operations in a well, said apparatus comprising:

well tool means fixedly positioned in a well bore and having tool actuating means associated therewith; operating means including

support means disposed in said well bore and operable to be lowered through said well bore from a wellhead, said support means including means for engaging and operating said tool actuating means, movable means mounted for longitudinal movement on said support means, first abutment means operable to provide force-transmitting engagement between said well tool means and said movable means, second abutment means operable to normally maintain said movable means in downward force-transmitting engagement with said support means in the absence of force-transmitting engagement between said well tool means and said movable means, and

fluid reaction means interposed between said support means and said movable means and operable, in response to force-transmitting engagement between said well tool means and said first movable means, to impede downward movement of said support means relative to said movable means as a function of the pressure of fluid in said well bore adjacent said movable means,

said fluid reaction means comprising:

annular piston means projecting generally laterally of a portion of said support means, generally annular cylinder means extending generally longitudinally of and carried by said movable means, and

said movable means being mounted on said support means, with said annular cylinder means telescopingly receiving said annular piston means,

said annular piston means facing generally upwardly, with the interior of said cylinder means being substantially isolated from the direct communication with fluid in said well bore, and with upper and lower ends of said movable means being exposed to said fluid, fluid reaction surface means on said support means and on said movable means oper-

11

able, respectively, to impart upwardly directed, fluid pressure generated force to said support means and downwardly directed fluid pressure generated force to said movable means corresponding generally to the product of the effective cross-sectional area of said piston means multiplied by the pressure of said well bore fluid adjacent said movable means; and

5
said first abutment means being operable in response to force-transmitting engagement between said well tool means and said movable means to cause said fluid reaction surface means to exert a lifting force on said support means generally in proportion to pressure of well bore fluid adjacent said movable means.

10
8. An apparatus for performing operations in a well, aid apparatus comprising:

15
packer means fixedly positioned in a well bore and including

20
central conduit means,
packer means securing said central conduit means to a wall portion of said well bore, and
valve means mounted for reciprocable movement within said central conduit means and operable 25 to control fluid flow from the interior to the exterior of said central conduit means,

25
operating means including
a conduit string disposed in said well bore and operable to be lowered through said well bore from 30 a wellhead, said conduit string including means for engaging and reciprocating said valve means, sleeve means mounted for telescoping longitudinal movement on said conduit string,

35
first abutment means operable to provide force-transmitting engagement between said central conduit means and said sleeve means,

40
second abutment means operable to normally maintain said sleeve means in downward force-transmitting engagement with said conduit string in the absence of force-transmitting engagement between said central conduit means and said sleeve means; and

45
fluid reaction means interposed between said conduit string and said sleeve means and operable, in response to force-transmitting engagement between said central conduit means and said sleeve means, to impede downward movement of said conduit string relative to said sleeve means as a function of the pressure of fluid in said well bore adjacent said sleeve means,

50
said fluid reaction means comprising

55
annular piston means projecting generally outwardly of the exterior of a portion of said conduit string,

55
generally annular cylinder means extending generally longitudinally of and carried by, the inner periphery of said sleeve means, and

60
said sleeve means being mounted on the exterior of said conduit string, with said annular cylinder means telescopingly receiving said annular piston means,

65
said annular piston means facing generally upwardly, with the interior of said cylinder means being substantially isolated from the direct communication with fluid in said well bore, and with upper and lower ends of said sleeve means being exposed to said fluid, fluid reaction surface means on said conduit

70
string and on said sleeve means operable, respectively, to impart upwardly directed, fluid pressure generated force to said conduit string and downwardly directed fluid pressure generated force to said sleeve

75

means corresponding generally to the product of the mutually identical effective cross-sectional areas of said piston means and cylinder means multiplied by the pressure of said well bore fluid adjacent said sleeve means; and

said first abutment means being operable in response to force-transmitting engagement between said central conduit means of said packer means and said sleeve means to cause said fluid reaction surface means to exert a lifting force on said conduit string generally in proportion to pressure of well bore fluid adjacent said sleeve means.

9. An apparatus for operating well tool means fixedly positioned in a well bore and having tool actuating means associated therewith, said apparatus comprising:

operating means including

support means disposed in said well bore and operable to be lowered through said well bore from a wellhead, said support means including means for engaging and operating said tool actuating means,

movable means mounted for longitudinal movement on said support means,

first abutment means operable to provide force-transmitting engagement between said well tool means and said movable means,

second abutment means operable to normally maintain said movable means in downward force-transmitting engagement with said support means in the absence of force-transmitting engagement between said well tool means and said movable means, and

fluid reaction means interposed between said support means and said movable means and operable, in response to force-transmitting engagement between said well tool means and said movable means, to impede downward movement of said support means relative to said movable means as a function of the pressure of fluid in said well bore adjacent said movable means, said fluid reaction means comprising

annular piston means projecting generally laterally of a portion of said support means, generally annular cylinder means extending generally longitudinally of and carried by said movable means, and

said movable means being mounted on said support means, with said annular cylinder means telescopingly receiving said annular piston means,

said annular piston means facing generally upwardly, with the interior of said cylinder means being substantially isolated from the direct communication with fluid in said well bore, and with upper and lower ends of said movable means being exposed to said fluid,

fluid reaction surface means on said support means and on said movable means operable, respectively, to impart upwardly directed, fluid pressure generated to force said support means and downwardly directed, fluid pressure generated force to said movable means corresponding generally to the product of the effective cross-sectional area of said piston means multiplied by the pressure of said well bore fluid adjacent said movable means; and

said first abutment means being operable in response to force-transmitting engagement between said well tool means and said movable means to cause said fluid reaction surface means to exert a lifting force on said support means generally in proportion to

13

pressure of well bore fluid adjacent said movable means.

10. An apparatus for operating a valve in a packer means fixedly positioned in a well bore and including central conduit means, packer means securing said central conduit means to a wall portion of said well bore, and valve means mounted for reciprocable movement within said central conduit means and operable to control fluid flow from the interior to the exterior of said central conduit means, said apparatus comprising:

10
operating means including

a conduit string disposed in said well bore and operable to be lowered through said well bore from a wellhead, said conduit string including means for engaging and reciprocating said 15 valve means,

sleeve means mounted for telescoping longitudinal movement on said conduit string,

first abutment means operable to provide force-transmitting engagement between said central 20 conduit means and said sleeve means,

second abutment means operable to normally maintain said sleeve means in downward force-transmitting engagement with said conduit string in the absence of force-transmitting engagement 25 between said central conduit means and said sleeve means, and

fluid reaction means interposed between said conduit string and said sleeve means and operable, 30 in response to force-transmitting engagement between said central conduit means and said sleeve means, to impede downward movement of said conduit string relative to said sleeve means as a function of the pressure of fluid in said well bore adjacent said sleeve means,

35 said fluid reaction means comprising

annular piston means projecting generally outwardly of the exterior of a portion of said conduit string,

40 generally annular cylinder means extending generally longitudinally of, and carried by, the inner periphery of said sleeve means, and

45 said sleeve means being mounted on the exterior of said conduit string, with said an-

nular cylinder means telescopingly receiving said annular piston means,

said annular piston means facing generally upwardly, with the interior of said cylinder means being substantially isolated from the direct communication with fluid in said well bore and with upper and lower ends of said sleeve means being exposed to said fluid,

fluid reaction surface means on said conduit string and on said sleeve means operable, respectively, to impart upwardly directed, fluid pressure generated force to said conduit string and downwardly directed fluid pressure generated force to said sleeve means corresponding generally to the product of the mutually identical, effective cross-sectional areas of said piston means and cylinder means multiplied by the pressure of said well bore fluid adjacent said sleeve means; and

said first abutment means being operable in response to force-transmitting engagement between said central conduit means of said packer means and said sleeve means to cause said fluid reaction surface means to exert a lifting force on said conduit string generally in proportion to pressure of fluid in said well bore generally adjacent said sleeve means.
